UNITED STATES PATENT OFFICE.

HENRY STONE AND WALTER H. PITTS, OF BROOKLYN, ASSIGNEES TO THE UNITED STATES WEIGHING MACHINE COMPANY, OF NEW YORK, N. Y.

COIN-CONTROLLED WEIGHING-MACHINE.

SPECIFICATION forming part of Letters Patent No. 393,593, dated November 27, 1888.

Application filed May 10, 1888. Serial No. 273,442. (No model.)

To all whom it may concern:

Be it known that we, HENRY STONE and WALTER H. PITTS, citizens of the United States, residing at Brooklyn, in the county of Kings 5 and State of New York, have invented a new and useful Coin - Controlled Weighing - Machine, of which the following is a specification.

Our invention relates to an improvement in weighing-machines operated by a coin dropped 10 into a chute; and the objects of our invention are, first, to provide such a machine as may be operated by a coin of any denomination that will fit the chute; second, to provide such a machine as will be operated by the coin 15 whether the person desiring to be weighed steps upon the weighing-platform either before or after dropping the coin into the chute; third, to provide such a machine as shall be self-winding; fourth, to provide such a machine as will not be liable to get out of order 20 through sudden jerks and rough usage. We attain these objects by the mechanism illustrated in the accompanying drawings, in which—

25 Figure 1 is a face or front view of our weighing-machine with part of the dial removed and without the weighing-platform. Fig. 2 is a vertical section of the weighing-machine without the case and dial and also without the 30 weighing - platform. Fig. 3 is a horizontal view of the machine on the line 3 3. Fig. 4 is a detail face view of the two revolving disks L and M. Fig. 5 is a sectional view of the same horizontally on the line 5 5. Fig. 6 is 35 a detail view of a portion of the pawl I' I' and the rod J. Fig. 7 is a detail view of the same horizontally. Fig. 8 is a detail view of the shouldered bearing V, shaft T', indicating-hand U, stop-bar V', stop-pin v, anti-friction 40 wheels f f, and cord f' f'.

The same letters refer to the same or like parts throughout.

The weighing-machine has a suitable case, A, provided with a suitable dial, A', a square-sided chute, F F', a face or bed plate, D, supported upon the case, and is provided with an upright T-shaped bar, B, connecting at the bottom with the weighing-lever of a suitable scale and at the top with two spiral springs, 45 C C, Figs. 1 and 2, securely hung upon an ad-

justable cross-piece, C' C', held in place by the screws C" C", the said springs C C being of sufficient strength to superbalance the weight of the bar B and its connections and prevent its dropping by the force of gravity when no 55 weight is on the platform of the scales. The bar B passes behind the face-plate D. Upon the face-plate D is a narrower bar, E, sliding vertically between suitable bearings, e" e", connected at its upper end with the piston-rod d 60 of a piston working in a cylinder, D, and terminating at its lower end in a small wheel, e', resting upon a flat metal strip, b", which will be hereinafter more fully described. The cylinder D' is fixed to the face-plate D. 65

Upon the face of the bar E and above the middle are two wheels, f f, and at one side, fixed at the point g', is a bow-spring, g g. Fastened to each end of the spring g g and passing over each of the wheels f f is a cord, 70 f' f', the intention of the wheels f f being to lessen the friction of the cord f' f'. About the middle of the bar E and on one of its sides is a ratchet, e.

Fixed upon the upper portion of the face-plate D is a shouldered bearing, V, (see Fig. 8,) through which at its lower end passes the shaft T' of an indicating-hand, U. Attached to the indicator-shaft T' and turning with it is a stop-bar, V', which when in normal position rests against a small stop-pin, v, Figs. 1 and 8.

The dotted lines V' in Fig. 2 represent the stop bar both in normal position and carried around with the indicating-hand U. The cord 85 f' f' before mentioned is passed around the indicator-shaft T', the bight or bights of the cord being passed through the shaft T' to prevent slipping.

Pivoted upon the face-plate D at the point 90 i is a pawl, I' I', with a counter-weight, I, this pawl engaging with the ratchet e. Attached to the pawl I' I' is a rod, J, working at one end with a slot, i'', over a pin, i', projecting from the pawl I' I', and having a small spring, 95 i'', upon its upper side, one end of this spring being caught under the pin i', Figs. 1, 2, 6, and 7. The rod J terminates at its other end in a rounded hook, j, which fits rounded incisions or cuttings in the disk L. 100

In the chute F', which is square-sided, pivoted at the point f'', is a lever-pan, F'', having a counter-weight, G'. With one end resting upon the lever-pan F'' is a lever, G G, pivoted upon a cross-bar, W, at the point H, and the other end terminating in a hook, w, which projects forward and rests upon a second lever, K, Figs. 2 and 3. This lever K is pivoted in a movement, S, upon a shaft, k, is weighted at the point k', and at this end rests upon the fly-wheel of a fly-fan, k'' k'''.

Upon the upper edge of the lever K is a tooth or projection, m', which fits incisions or cuttings m in the rim of the disk M. Firmly fixed to and revolving with the shaft T of the movement S is a heavy disk, L, having on its rim at regular intervals semicircular cuttings or incisions n n, with their points rounded off, Figs. 2, 4, and 5. The rear side of the disk L is recessed to admit the introduction of a small coil-spring, t. Through the disk is cut a slot, u'. Revolving upon the shaft T is a second and much thinner disk, M, having upon its rim rectangular incisions or cuttings m m, Figs. 2, 4, and 5, and upon its front face a pin, u, working in the slot u' of the disk L. The circles shown upon this disk M in Fig. 4 are merely cuttings to lessen the weight, and do not relate to the mechanism. The small spring t, recessed into the disk L, is fastened at one end to the shaft T and at the other end to the pin u, Figs. 4 and 5.

Upon the movement S, pivoted at the point r, is a lever, R, having at one end a pawl, Q, pivoted at q, which fits a winding ratch-wheel, P, of the movement S, the said wheel P being rigidly fixed on the shaft N, this pawl Q being held against the wheel P by a small spring, r''. The lever R passes behind the bar B and rests upon a pin, r', (shown in outline, Fig. 2,) projecting from the rear side of the bar B. Upon the opposite side of the winding-wheel P is a retaining-pawl, Q'. Revolving upon a winding-shaft, N, is a barrel, O, which has within it the driving-spring n' n'' of the movement S, one end, n', of which spring n' n'' is fastened to the shaft N, and the other end, n'', merely rests against the inner periphery of the barrel O.

At the lower part of the bar B is fixed a heavy metal stop-plate, B', with a shoulder, b. Upon the shoulder b, pivoted at b'', is a flat strip of metal, b'', weighted at the end b', and with its other end resting against a cushion, b', of rubber or other suitable material.

The cross-piece W is fastened and held in place by screws or rivets on the outside of the case of the movement S, Fig. 1. The fly-fan k'' k''' is an ordinary fly wheel and fan, such as is commonly used to regulate clock-movements.

The portions of the movement S not lettered or described are merely a train of gear-wheels to prevent the movement from running down too quickly.

Upon the bar B, at nearly its lowest point and on its rear side, is a stop-pin, B'', Fig. 1,

which when the bar B is in its normal position will rest against a cushion, B'', fixed to the case A, the intention being to prevent any undue pressure on the cushion or buffer b' and the end of the sliding bar E in case of ill use of the machine by sudden jumps upon the weighing-platform and the rebound when a person leaves the platform.

The action of the weighing machine is as follows: The coin falling upon the lever-pan F'' causes it to turn upon its pivot f'' and lift the end of the lever G G. The hook w being pressed downward upon the lever K lifts the weighted end k' thereof off the fly-wheel of the fly-fan k'' k''', and at the same time releases the tooth or projection m' of the lever K from the incision m of the disk M and allows the movement S to commence running. The disk M commences to turn slightly before the disk L, owing to the accelerating action of the small spring t; but this accelerating motion continues only while the pin u travels the length of the slot u', and the intention of it is to prevent the possibility of the projection or tooth m' of the lever K from falling back into the cutting m that it has just left. The disk M then, being slightly in advance of the disk L, is brought back to its original position with the disk L by the friction of the projection m' of the lever K upon the rim of the disk M, Fig. 4, this friction being sufficient to overcome the power of the small spring t and yet not sufficient to stop the action of the entire movement S. It is necessary for the disk M to be brought back to its original position with the disk L, as otherwise, the pin u being at the end of the slot u', it would be impossible for the accelerated motion of the disk M to be repeated when the next person is to be weighed. The rounded hook j on the rod J, being in place in a rounded incision, n, in the disk L, will be drawn in the direction that the disk L moves, carrying with it the pawl I' I''. This releases the sliding bar E. The person desiring to be weighed steps or has stepped upon the weighing-platform, causing the bar B to be drawn downward, the stop-plate and shoulder B' b being drawn with it. The sliding bar E falls of its own momentum, being prevented from acting too rapidly by the dash-pot D' d, this movement of the bar E causing, by means of the spring g g, the wheels f f, and the cord f' f', the indicator-shaft T' to turn with the indicating-hand U, showing upon the dial A' the weight of the person being weighed. In case a sudden jerk should cause the indicating-hand to go beyond the proper weight, it is brought back by the spring g g exerting an equal tension on each end of the cord f' f'. Through the action of the movement S the disk L turns from right to left, and the hook j of the rod J, being inserted in a cutting, n, is drawn in the direction L moves as far as the pawl I' I'', turning upon its pivot i, will allow it to go. The continued movement of the disk L causes the hook j to be drawn out of

the cutting n'' and released, the points of these cuttings being rounded off to allow such release. The counter-weight I of the pawl I' I' carries the rod J, and with it the pawl, back into place against the ratchet e. Should the pawl I' I' return to its normal position before the person steps off the platform, the slot i'', the pin i', and the spring i'', giving the pawl a slight play, allow the ratchet e to continue on its upward course, Figs. 6 and 7. The projection m' of the lever K is again inserted in one of the cuttings m of the disk M. The weighted end k' falls back upon the wheel of the fly-fan k'' k''' and the movement S is stopped. The person weighed steps off the platform, the bar B returns to its original position, carrying with it the sliding bar E, through the pressure of the stop-plate B' b, and the indicating-hand returns upward to zero, being prevented from going too far in case of sudden jerk by the stop-piece and pin V' v.

When the weighing-machine is first put together, the spring n' n'' of the movement S is wound sufficiently to start the mechanism. The subsequent winding is as follows: The weight of the person draws down the bar B and causes the lever R, which rests upon the pin r', to drop. The pawl Q then glides over the ratchet of the winding-wheel P. On the return of the bar B the pin r' lifts the lever R upward, which carries the pawl Q downward, and this pawl, being pressed against the ratchet of the wheel P by the spring r'', takes the wheel P around with it. When the pawl Q is released, the wheel is prevented from returning to its former position by the second pawl, Q', so winding the spring n' n'' in the barrel O, the winding-wheel P being loosely mounted on the shaft N, the wheel and barrel turning on the shaft N, but not with it, the shaft only turning when the winding takes place. As continued winding would break the spring n' n'' if it were fastened at both ends n' n'', it is not fastened at the point n'', but merely rests against the inner side of the barrel O, the friction of the spring on the inner side of the barrel holding it sufficiently to wind it to drive the movement. Thus any extra winding force exerted on the spring does not cause it to break, but merely to revolve in the barrel.

As the bar B in returning to its normal position has to exert some of its force in winding the machine, the tendency is not to push the sliding bar E fully back to its normal position—that is, the indicating-hand fully back to the zero-point. To obviate this a flat strip of metal, b'', is pivoted upon the shoulder b at b''' and weighted at b', one end of which comes into contact with a cushion or buffer, b⁴, of rubber or suitable material. This contact causes the end b' to press upward against the end of the sliding bar E, carrying it back to its original position, Fig. 1. The wheel e' is to lessen friction and provide for any slight lateral motion of the bar E in its bearings.

The weight b' causes the strip b'' to fall back in place on the shoulder b.

Having fully described our invention, what we desire to claim and secure by Letters Patent is—

1. The combination, in a coin-controlled weighing-machine, with platform, index, and a connection between them, of the cylinder and piston D' d, the sliding bar E, the anti-friction wheels f f and e', the ratchet e, the bow-spring g g, the shaft T', and the cord f'' f', passing in bights around and through the shaft T', substantially as set forth. 75

2. The combination, in a weighing-machine, so with a platform connected with a weighing-lever, of the sliding bar B, connected with said lever so as to slide in consonance therewith, and being superbalanced by springs and carrying a stop, the bar E, having ratchet e, and resting on said stop when its action is free or on a cushion thereon, but otherwise disconnected with bar B, the index U, with its connections with bar E, as described, so that its movement is regulated by the rise and fall of 90 said bar, the tumbler-lever F'' for receiving the coin, the pawl I' I', the motor S, and connections, substantially as herein described, between said tumbler-lever and the said pawl, whereby the weight of the coin is made to disengage the pawl I' I' from the ratchet e, as 95 herein set forth.

3. The combination, in a weighing-machine controlled by a coin, of the tumbler-lever F'', the motor S, and the pawl I' I', with their connections through the motor, the free sliding bar E, having ratchet to engage said pawl and connected with index U, as described, and bar B, sliding in consonance with the platform weighing-lever, and having a stop which controls the free movement of rod E, as herein set forth. 100

4. The combination, in a weighing-machine, of a sliding bar, E, connected, as herein described, with an index, and whose movement 110 is controlled by a stop upon bar B, connected, as herein described, with the platform, the metal strip b'', pivoted to said stop and having thereon the weight b' at one end, and the other end resting against a cushion, b⁴, the cushion b⁴, the bar E, controlling the index, and bar B, connected with the platform, as herein set forth. 115

5. In a weighing-machine, the combination of the tumbler-lever F'', hooked lever-bar G 120 G w, weighted releasing-bar K k' m', the notched or incised disks L n M m, the movement or motor S, rod J j, pawl I' I', and ratchet e, as described.

6. The combination of the disk L, having 125 incisions n n, the disk M, having incisions m m, the lever K, provided with tooth m', the rod J j, pawl I' I', motor S, bar G G, and tumbler-lever F'' and bar B, with platform and its connections thereto, as described. 130

7. The combination, in a weighing-machine, with the platform and ratchet e, and connec-

tions between them, as described, of the disk L *n*, coil-spring *t*, pin *u*, and disk M *m*, having slot *u'*, lever K, and lever J, as described.

8. The combination, in a weighing machine, 5 with the platform and ratchet *e*, and connections between them, as described, and motor S, of the rod R R, driving pawl Q, ratchet-wheel P, retaining-pawl Q', bar B, and stop r', as described.

10 9. The combination, in a coin-controlled

weighing machine, with the bar B, of the shouldered stop-plate B' b, the pivoted and weighted horizontal strip b'' b', and the buffer or cushion b⁴, and the bar E, connected with a dial, substantially as set forth.
